(57) **CLAIM**

We claim the ornamental design for a battery receptacle, as shown and described.

DESCRIPTION

FIG. 1 is a front-left perspective view from above of the claimed design according to one embodiment;

FIG. 2 is a detail view of a portion of the claimed design of FIG. 1;

FIG. 3 is a front-right perspective view of the claimed design of FIG. 1;

FIG. 4 is a detail view of a portion of the claimed design of FIG. 3;

FIG. 5 is a left side view of the claimed design of FIG. 1;

FIG. 6 is a right side view of the claimed design of FIG. 1;

FIG. 7 is a rear side view of the claimed design of FIG. 1;

FIG. 8 is a front view of the claimed design of FIG. 1;

FIG. 9 is a detail view of a portion of the claimed design of FIG. 8;

FIG. 10 is a top view of the claimed design of FIG. 1; and, FIG. 11 is a detail view of a portion of the claimed design of FIG. 10.

The broken lines in the drawings are for illustrative purposes only and form no part of the claimed design. Broken lines formed by equal length dashes show unclaimed portions of the design. Broken lines formed of unequal length dashes (i.e., dash-dot) show boundaries between claimed and unclaimed portions of the design.
